UNITED STATES PATENT OFFICE.

WILLIAM R. OSTRANDER, OF NEW YORK, N. Y.

DESIGN FOR SPEAKING-TUBES.

Specification forming part of Design No. **11,544**, dated December 16, 1879; application filed November 28, 1879.
[Term of patent 14 years.]

To all whom it may concern:

Be it known that I, WILLIAM R. OSTRANDER, of New York, in the county of New York and State of New York, have originated and invented a new and useful Design for Speaking-Tubes; and I do hereby declare that the following is a full, clear, and exact description thereof, reference being had to the accompanying drawing, forming a part of this specification, in which—

A designates a shell or barrel, which is formed with a cylindrical part, *a*, beveled ends *b*, terminating in vertical parallel sides *b'*, and an annular rib, *c*, upon the cylindrical part *a*, and located intermediate of the beveled ends.

D designates the flaring or bell-mouthed mouth-piece, which extends out from one end of the shell or barrel A, and E a cylindrical

tube, which extends out from the remaining end of the said shell, all substantially as shown.

What I claim is—

The design for a speaking-tube whistle having the shell or barrel A, with a cylindrical part, *a*, beveled ends *b*, terminated by parallel flat surfaces *b'*, annular rib *c* upon its cylindrical part and intermediate of its ends, and the flaring mouth-piece D, projecting from one end of the shell or barrel, substantially as shown.

In testimony that I claim the foregoing as my own I affix my signature in presence of two witnesses.

WILLIAM R. OSTRANDER.
